UNITED STATES PATENT OFFICE.

DAVID L. SUMMEY, OF WATERBURY, CONNECTICUT, ASSIGNOR TO CHASE ROLLING MILL CO., OF WATERBURY, CONNECTICUT, A CORPORATION.

METHOD OF AND MACHINE FOR EXTRUDING METAL.

1,011,522.

Specification of Letters Patent. Patented Dec. 12, 1911.

Application filed March 10, 1910. Serial No. 548,451.

To all whom it may concern:

Be it known that I, DAVID L. SUMMEY, a citizen of the United States, residing at Waterbury, in the county of New Haven and State of Connecticut, have invented a new and useful Improved Method of and Machine for Extruding Metal; and I do hereby declare the following, when taken in connection with the accompanying drawings and the letters of reference marked thereon, to be a full, clear, and exact description of the same, and which said drawings constitute part of this specification, and represent, in—

15 Figure 1 a plan view in the nature of a diagram, of one form which an extrusion machine constructed in accordance with my invention may assume. Fig. 2 a broken view, on a larger scale, in horizontal section, 20 through the container and cylinders of my improved machine, the outer ends of two of its four arms being broken away, and the mandrel and die being advanced into their operating positions in the billet-chamber 25 of the container. Fig. 3 a broken view in horizontal section of the main-casting showing the container and a billet positioned therein for which purpose the mandrel and die and the rams have been retired and are 30 not shown. Fig. 4 a corresponding but more comprehensive view showing the mandrel and die in their operative positions and the rams as advanced upon the ends of the billet to force the metal past 35 the mandrel and die in the production of an extruded tube. Fig. 5 a broken view in vertical section on the line *a*—*b* of Fig. 4 showing the provision for longitudinally adjusting the container in the main-casting 40 as well as for preventing its rotation therein. Fig. 6 a broken view of the machine in vertical section on the line *c*—*d* of Fig. 2, showing the main-casting, the container and the mandrel and die which latter are 45 represented in their retired positions. Fig. 7 a broken view of the main-casting in side elevation, showing the mechanism employed for locking the mandrel and die in their operative positions. Fig. 8 a broken view 50 partly in side elevation and partly in vertical section of one of the main hydraulic cylinders. Fig. 9 a corresponding view of one pair of the auxiliary hydraulic cylinders.

55 My invention relates to an improved

method of, and machine for, extruding metal tubes, rods and the like, the object being to produce extruded metal stock of superior quality and at a reduced cost.

With these ends in view my invention 60 consists in the method and machine to be hereinafter described and pointed out in the claims.

In carrying out my invention, I employ a horizontally arranged cylindrical container 2 formed with a central, horizontal billet-chamber 3 open at both ends. As shown, the billet-chamber 3 is circular, but its cross-sectional form may be varied as found expedient. The said container 2 is 70 also formed with a transverse passage shaped like an hour-glass, open at both ends and intersecting the said billet-chamber 3 midway the length thereof and at a right angle thereto. This passage forms 75 two conical centering-chambers 4 for the reception, respectively, of the conical holders 5 and 6 of the mandrel 7 and die 8.

In practicing my improved method, a billet 9, preferably heated and relatively long 80 as compared with its diameter, is introduced into the billet-chamber 3 at a time when the said mandrel 7 and die 8 are entirely retired therefrom. The billet is solid, and by the term "solid" I refer to the condition of the billet which is sufficiently rigid to retain its shape while being introduced into the billet chamber and not to the shape or form of the billet which, if desired, might be perforated or hollow. After the billet 85 has been positioned in the said chamber, the mandrel and die are advanced thereinto, and embedded and positioned in the billet the waist of which, so to speak, they enter. The billet is then subjected to pressure upon 90 its opposite ends, causing the metal comprising it to flow at a right angle to its axial line around the mandrel 7 and through the die 8 in the form of a tube.

The said container 2 is formed, as shown, with a centrally arranged wide external rib 10 the continuity of which is broken at opposite points by the two conical centering-chambers 4 already described. The said rib 10 is registered, when the container is 105 in position, with a corresponding internal rib 11 centrally located within a cylindrical opening 13 adapted in diameter to receive the container 2 and formed in a main casting 14 resting upon bed-plates 15. The op-

posite ends of the opening 13 are threaded for the reception of bushing-like nuts 12 respectively encircling the ends of the container and bearing against the opposite 5 edges of its rib 10. These bushings prevent the container from moving in the main-casting but permit it to be longitudinally adjusted therein.

For simultaneously subjecting the billet 9 10 to endwise pressure at both ends in the chamber 3, I employ two corresponding rams 16 operated by duplicate mechanisms located on the opposite sides of the main-casting 14 but in line with each other and 15 in line with the said chamber 3, each of these mechanisms constituting an arm of the machine when the same is viewed broadly as in Figs. 1 and 2.

Each ram 16 is secured by a head 17 to 20 a guide-block 18 traveling back and forth upon corresponding columns 19 passing horizontally through holes 20 in the main-casting 14 from the opposite sides of which they project for equal distances, being held 25 against endwise movement in the holes 20 by their provision with nuts 21 bearing against the sides of the said casting. Each guide-block 18 is carried by a plunger 22 operated by a hydraulic cylinder 23 formed 30 on opposite sides with sleeves 24 receiving the ends of the columns 19. The cylinders 23 are thus fixed in their relation to the main-casting 14. Locking nuts 25, 26, mounted upon the ends of the columns 19 35 position the sleeves 24 and hence the cylinders 23.

Water for the operation of the plungers 22 is admitted to the cylinders 23 through openings 27 in the outer ends thereof from 40 water-supply pipes 27a. Each of the plungers 22 is retracted after it has done its work by means of four draft-rods 28 fastened at their inner ends to the guide-blocks 18 and having their outer ends connected to yokes 29 respectively actuated by pistons 30 entered at their inner ends into small auxiliary hydraulic cylinders 31 located above and below the main cylinder 23. Water pressure tending to move the plungers 22 outward is constantly maintained in 50 the auxiliary hydraulic cylinders 31, but is only effective when the water pressure is removed from the main cylinders 23.

In using the machine, the billet 9 will be 55 placed by suitable delivering means, not shown, in front of one of the rams 16 after which the two rams will be advanced simultaneously, whereby the billet will be introduced into the chamber 3 and then subjected 60 to endwise compression by the simultaneous advance of the rams into the opposite ends of the said chamber, as will be described later on.

After a billet has been introduced into 65 the billet-chamber 3, the mandrel 7 and die

8 will be simultaneously advanced from opposite directions into the billet midway the length thereof and at a right angle to its longitudinal axis. The mechanism for operating the mandrel 7 is substantially the 70 same as the mechanism for operating the die 8. These mechanisms are arranged in line with each other at a right angle to the line of the mechanisms already described for operating the two rams 16, the effect of 75 the whole machine being that of a large cross of four arms as already stated. The mandrel and die operating mechanisms employ conical holders 5 and 6 conformed in shape to the conical centering-chambers 4 80 to insure the centering respectively of the mandrel 7 and the die 8 and to hold them firmly in their operating positions against lateral thrust.

The hollow die-holder 5 carrying the die 8 is screwed into a conical coupling-sleeve 32 mounted upon the inner end of a long hollow stem 33 having an annular shoulder 34 about midway of its length and non-rotatably mounted in a cross-head 35 the 90 ends of which are connected with the inner ends of piston-rods 36 the outer ends of which terminate in double-acting pistons 37 working in cylinders 38 mounted in a supporting casting 39. The said cross-head 95 35 is moved back and forth upon horizontal columns 40 fastened at their inner ends by nuts 41 in the main-casting 14 while their outer ends are fastened by nuts 42 to the supporting casting 39. A nut 43 applied to 100 the threaded outer end of the stem 33 and bearing against the outer face of the cross-head 35, draws the annular shoulder 34 of the stem 33 against the inner face of the cross-head 35 and holds the said stem 105 against rotation in conjunction with a key 44. By preference I employ a guide-tube 45 having its inner end connected to the nut 43 and arranged in line with the hollow stem 33, to receive and guide the product of the 110 machine. The mechanism provided for operating the mandrel 7 is the same as the mechanism already described, barring the provision for the escape of the extruded product of the machine. Thus the conical mandrel-holder 5 is solid rather than hollow and so on.

For locking the mandrel 7 and die 8 in their operating positions against outward thrust, I employ locking mechanisms which, 115 as shown, are duplicates of each other. Each of these mechanisms consists of a sleeve 46 having interrupted threads and mounted for partial rotation upon the stem 33 at a point between the coupling-sleeve 120 32 at its forward end and the annular shoulder 34 before mentioned. The interrupted exterior threads of these sleeves take into 125 corresponding interrupted threads formed upon the inner faces of bushings 47 located 130

in threaded chambers 48 in the main-casting 14.

When the mandrel 7 and die 8 have been advanced into their home positions and their conical holders 5 and 6 have been firmly seated in the centering chambers 4 in the container 2, the said holders, and therefore the die and mandrel, are firmly locked in such positions by means of the said locking-sleeves 46 which have advanced correspondingly with the hollow stems 33. The locking-sleeves 46 are now rotated a one-eighth turn as required for interlocking their interrupted threads with those of the bushings 47. For turning the locking-sleeves 46, I employ operating-rings 49 encircling their outer ends and located within housings 50 secured by bolts 51 to the main-casting 14. The said rings 49 are encircled by roller-bearings 52 and provided with toothed segments 53 meshing into racks 54 mounted on double-ended piston-rods 55 the respective ends of which enter locking-cylinders 56 and unlocking cylinders 57 to 20 which water under pressure is admitted as required to move the racks 54 so as to turn the operating-ring 49 in one direction or the other as required for locking or unlocking the said locking-sleeves 49.

30 For non-rotatably mounting the operating-rings 49 upon the outer ends of the locking-sleeves 46, the said rings are formed with wide locking-ribs 58 which enter clearance spaces 59 between the interrupted threads of the said sleeves, whereby the same are free to be moved back and forth with respect to the rings, but when once entered thereinto are non-rotatably coupled therewith.

40 Having now described my improved machine, I will now set forth the method of its operation.

A relatively long billet 9, preferably cylindrical, though the cross-section form of 45 the billet is immaterial, is placed by any suitable delivery mechanism, before one or the other of the two rams 16 after which the said rams are simultaneously moved inward toward each other, whereby the billet is 50 entered into the billet-receiving chamber 3 in the container 2, the mandrel 7 and die 8 being at this time in their retired positions, or, in other words, at the limit of their outward excursions. The billet having thus 55 been positioned in the billet-chamber 3, the mandrel 7 and die 8 are simultaneously advanced toward each other in a line at a right angle to the line passing through the billet and the rams 16, and enter the waist of the 60 billet at opposite points in the perimeter thereof and midway of its length. By the entrance of the die 8 into the billet, the metal thereof is tapped off, so to speak, from a point within the perimeter thereof and hence 65 from a point not so liable to be chilled by the container as any point on its perimeter from which, however, the metal might be tapped though I prefer not to do it, for the reasons stated. When the mandrel and die have been positioned, as described, and 70 locked in place by the mechanism provided for the purpose, the rams 16 are simultaneously advanced upon the opposite ends of the billet which is then in this way subjected to such pressure that it flows around 75 the mandrel and through the die and into the passage 6^a of the die-holder 6, taking the form of a tube which passes through the hollow stem 33 and then out through the guide-tube 45. At the conclusion of the extruding operation, the holders 5 and 6 are withdrawn by the outward movement of the cross-heads 35, whereby the mandrel 7 and die 8 are entirely cleared from the billet-chamber 3 after which the "stump" or unextruded end of the billet will be ejected in any convenient manner from the said chamber before the introduction of another billet thereinto. The retirement of the mandrel and die for the introduction of a solid billet 80 into a container and the embedding of the mandrel and die of the mandrel alone in the billet prior to subjecting the same to pressure, are the salient features of my present invention. 85

It will be understood, of course, that the different parts of the machine herein shown and described will be timed to act in the order above stated, and that the timing of the machine will be regulated by the action 100 in suitable concert of valves, not shown, but placed so as to control the several pressure-cylinders of the machine.

In case it is designed to extrude rods, the solid holder 6 will be replaced by a holder 105 like the holder 5 and the mandrel 7 by a die like the die 8. Under this arrangement the metal of the billet will flow from its center in opposite directions, and two rods, round, square, pentagonal or of any other 110 cross-sectional form, will be simultaneously produced; or, if desired, a plurality of dies might be mounted in each die-holder so as to produce a plurality of cross-sectionally solid rods which would be extruded in opposite directions. By providing one holder with a plurality of mandrels and the other holder with a plurality of dies, a plurality of tubes might be simultaneously extruded, all in the same direction. Other dies might 120 also be located in the central portion of the billet-receiving chamber so as not to interfere with the mandrel 7 and die 8, but so as to tap off some of the metal of the billet.

I claim:—

1. A method of extruding metal consisting in positioning a billet in a billet-receiving chamber formed in the container, then simultaneously subjecting the opposite ends of the billet to inward pressure for the ex- 130

trusion of the metal which is shaped by a mandrel and a die, and then retiring the mandrel from the container to permit the expulsion of the "stump" of unextruded metal from the said chamber and the introduction of another billet.

2. A method of extruding metal consisting in positioning a billet in a container, then embedding a mandrel in the billet, then 10 simultaneously subjecting the opposite ends of the billet to inward pressure for the extrusion of the metal which is shaped by the mandrel and a die, and then retiring the mandrel from the container to permit 15 another billet to be introduced thereinto.

3. A method of extruding metal consisting in positioning a billet in a container, then advancing a mandrel into the container and billet at a right angle to the longitudinal 20 axis thereof, then simultaneously subjecting the opposite ends of the billet to pressure for the extrusion of the metal, and then retiring the mandrel from the container to permit the introduction of another billet 25 thereinto.

4. A method of extruding metal consisting in positioning a billet in a container, then advancing a mandrel and a die from opposite directions into the container at a 30 right angle to the longitudinal axis of the billet, then subjecting the opposite ends of the billet to pressure, and then retiring the mandrel and die for the introduction of another billet into the container.

5. In an extrusion machine, the combination with a container, of means for subjecting a billet to pressure therein, a mandrel, a die, and means for advancing the mandrel into the container to embed it in a billet 40 therein and for retiring the mandrel from the container preparatory to the introduction of a billet thereinto.

6. In an extrusion machine, the combination with a container, of rams for subjecting 45 the billet to pressure after its introduction thereto, a mandrel located at a right angle to the rams, and means for reciprocating the mandrel whereby the same is embedded in the billet after the same has been introduced 50 into the container, and whereby the mandrel is retired from the container to permit the introduction of another billet thereinto.

7. In an extrusion machine, the combination with a container having a billet chamber, of two rams for simultaneously entering 55 the opposite ends of the said chamber, a mandrel and a die respectively entering the opposite sides of the said chamber, and means for retiring and advancing the said 60 mandrel and die before and after the introduction of a billet thereinto.

8. In an extrusion machine, the combination with a container having a billet-chamber, of two rams for being simultaneously

advanced into the opposite ends of the said 65 chamber after the introduction of a billet thereinto, a mandrel entering the said chamber at a right angle to the line of the said rams, and means for advancing the said mandrel to embed it in a billet in the said 70 chamber and for retiring the mandrel from the said chamber preparatory to the introduction of a billet thereinto.

9. In an extrusion machine, the combination with a container having a billet-chamber, 75 and two conical centering chambers located in line with each other but at an angle with respect to the longitudinal axis of the said billet-chamber, rams for entering the opposite ends of the billet-chamber, 80 conical holders adapted to be centered in the said conical centering chambers, means for operating the holders back and forth at a right angle to the movement of the rams, and means carried by the said holders for 85 shaping the metal extruded.

10. In an extrusion machine, the combination with a container having a billet-chamber open at both ends, of rams entering the opposite ends of the billet-chamber, a mandrel and a die, means for advancing them in a line at a right angle to the movement 90 of the rams after the billet is in place in the said chamber, and means for locking the said mandrel and die in their advanced 95 positions.

11. In an extrusion machine, the combination with a container having a billet-chamber open at both ends, of rams for being simultaneously advanced into the opposite 100 ends of the said chamber, a mandrel and a die entering the said chamber through openings in the sides of the container, holders for the said mandrel and die, and means for operating the said holders to advance the 105 said mandrel and die after the billet is in place in the said chamber.

12. In an extrusion machine, the combination with a container having a billet-chamber open at both ends, of rams entering the 110 opposite ends thereof, a mandrel and a die entering the billet-chamber at a right angle to the rams, holders for the said mandrel and die, means for advancing the said holders after the billet is in place in the said chamber, locking devices for the holders, and means for operating the said locking-devices.

13. In an extrusion machine, the combination with a container having a billet-chamber, of two rams entering the opposite ends of the said chamber, a mandrel and a die entering the said chamber from the opposite sides thereof, holders carrying the said mandrel and die, locking means for locking the 120 said mandrel and die holders in their advanced positions, and racks and pinions for operating the said locking means.

14. In an extrusion machine, the combination with a container having a billet-chamber, of rams entering the opposite ends of the said chamber, a mandrel entering the 5 said chamber through the side thereof, locking means for the said mandrel, and means for automatically operating the said locking means.

15. In an extrusion machine, the combination with a container having a billet-chamber, of rams entering the opposite ends of the said chamber, a mandrel and a die entering the said chamber through the opposite sides thereof, holders for the said mandrel 15 and die, cross-heads in which the holders are mounted, and cylinders connected with the ends of the cross-heads for operating the same, whereby the cylinders are located on either side of the path of the metal extruded.

16. In an extrusion machine, the combination with a main-casting having a container-chamber, of a container located in the said chamber, means for positioning the said 25 container in the said chamber by moving it endwise therein, rams entering the billet-chamber in the container, a mandrel entering the billet-chamber through the side thereof, and means for advancing and 30 retiring the mandrel after the positioning of a billet in the billet-chamber.

17. In an extrusion machine, the combination with a main-casting having a container-chamber, of a container located therein, 35 threaded positioning rings located in the opposite ends of the said chamber for positioning the container in the main-casting, rams entering the opposite ends of the billet-chamber in the container, a mandrel and a 40 die entering the side walls of the billet-chamber through openings in the sides of the said container, and means for operating the said mandrel and die.

18. In an extrusion machine, the combination with a container having a billet-chamber open at both ends for the introduction of the billets, and with two conical centering chambers located at a right angle to the longitudinal axis of the said billet-chamber; of rams arranged to enter the ends of the billet-chamber, two conical holders respectively entering the centering-chambers, and metal-shaping tools mounted in the said 50 holders.

55 19. In an extrusion machine, the combination with a container formed with a billet-chamber open at its ends for the introduction of the billets, and with two conical centering-chambers located in line with each 60 other and at a right angle to the longitudinal axis of the billet-chamber, of rams for entering the opposite ends of the said billet-receiving chamber, conical holders entering the said conical centering-chambers, means

for advancing the said holders after the introduction of the billets and for retiring the holders for the expulsion of the "stumps" of unextruded metal and the introduction of fresh billets, and metal-shaping tools mounted in the holders.

70 20. In an extrusion machine, the combination with a container formed with a billet-receiving chamber open at its ends for the introduction of the billets and with two centering-chambers located in line with each other and at a right angle to the longitudinal axis of the billet-chamber, of rams arranged to enter the opposite ends of the said billet-receiving chamber, two holders respectively entering the said centering-chambers, and metal-shaping tools mounted in the said holders.

80 21. A method of extruding metal consisting in inserting a solid billet in a billet-receiving chamber, then subjecting the billet to endwise pressure in the billet-receiving chamber and extruding the metal through an opening arranged at an angle to the line of pressure.

85 22. A method of extruding metal consisting in inserting a solid billet into a billet-receiving chamber, then subjecting the opposite ends of the billet to inward pressure and extruding the metal through an opening in the side of the chamber.

90 23. A method of extruding metal consisting in inserting a solid billet into a billet-receiving chamber, then subjecting the opposite ends of the billet to inward pressure for the extrusion of metal through a die located midway the length of the billet, and then retiring the die for cooling, then expelling the stump or unextruded portion of the billet.

100 24. A method of extruding metal consisting in positioning a billet in a billet-receiving chamber, then simultaneously subjecting each end of the billet to inward pressure for the extrusion of the metal through an opening in the side of the said chamber and around forming tools arranged at an angle to the line of pressure, and then retiring the said forming tools from the said chamber for the extrusion of the stump and the insertion of another billet.

110 25. A method of extruding metal consisting in positioning a billet in a billet-receiving chamber, then simultaneously subjecting each end of the billet to inward pressure for the extrusion of the metal through a die opening outward from the said chamber at an angle to the line of pressure, and then removing the stump from the said chamber preparatory to the introduction of another billet.

120 26. A method of extruding metal consisting in positioning a billet in a billet-receiving chamber, then simultaneously subjecting

each end of the billet to inward pressure for the extrusion of the metal around a mandrel located in the chamber and through a die opening out of the side of the chamber at an angle to the line of pressure, then removing the mandrel from the chamber and then removing the stump from the chamber.

In testimony whereof, I have signed this specification in the presence of two subscribing witnesses.

DAVID L. SUMMEY.
